[57] CLAIM

The ornamental design for a one-piece dome ceiling
with lip, as shown.

DESCRIPTION

FIG. 1 is a top plan view of a one-piece dome ceiling
with lip showing my new design;

FIG. 2 is a front elevational view thereof, the rear being
a mirror image;

FIG. 3 is a bottom plan view thereof;

FIG. 4 is a right side elevational view thereof, the left
side being a mirror image; and

FIG. 5 is a sectional view along line 5—5 of FIG. 1.

FIG. 1

FIG. 2

FIG. 3

FIG. 5

FIG. 4
